AMUSEMENT MACHINE

John F. Meyer, Pasadena, Calif.

Application January 18, 1932. Serial No. 587,295

5 Claims. (Cl. 212—42)

This invention relates to amusement machines of the kind delivering prizes proportioned in value to the skill of the operator of the machine.

The amusement machine of this invention is provided with a device under the control of the operator which is adapted to pick up articles from a table and deliver them to a discharge chute for passage from the machine to the operator. The device picking up the articles is suspended from a structure which is movable in both vertical and horizontal planes and a portion of the structure is under direct control of the operator while the remaining portions of the structure are operated in an automatic manner upon each operation of the device and this automatic operation is brought about by means not under the control of the operator.

One of the objects of this invention is to provide a novel structure for supporting the device which picks up the prizes and which structure is of simple and economical construction and efficient and positive operation.

Another object is to provide a structure wherein in the movement of a portion of the devices under the control of the operator may be confined within definite limits.

A still further object is to provide a novel structure embodying spring devices open to view so that breakage thereof may be readily detected and wherein the movable parts will be so arranged that seizing thereof will be prevented and so that the operation may be easily viewed so as to determine whether or not the devices are operating in a proper manner.

A selected embodiment of the invention is shown in perspective in the single figure of the accompanying drawing.

My invention, as illustrated in the accompanying drawing, is adapted to be used in a vending machine enclosed in a suitable cabinet (not shown) wherein there is a horizontal table 1 having an opening 2 therein and a suitable discharge chute or the like leads from this opening so that articles 3 lifted from the table 1 by the pick-up device 4 may be dropped through the opening into the discharge chute to pass from the machine. A discharge chute adaptable for this purpose is shown in the co-pending application of Victor Neumann, Serial No. 588,553, filed January 25, 1932. Supported from the frame of the machine by a bracket 5 is a bearing 6 in which a hollow shaft 7 is journaled. Extending through the hollow shaft 7 is a shaft 8 having a worm gear 9 fast on the upper end thereof. The shaft 8 is connected to a suitable source of

power such as an electric motor by which it is rotated for a predetermined length of time upon each operation of the machine. Fast to the shaft 7 and resting on the upper end of the bearing 6 are brackets 10 and 11 having a shaft 12 journaled therein on which a worm wheel 13 is fast and the worm wheel 13 meshes with the worm gear 9. On each side of the worm wheel 13 are cams such as 14. Connected to the forward ends of the brackets 10 and 11 are arms 15 and 16 which are curved so as to clear the cams on each side of the worm wheel 13 and which terminate in upwardly extending portions arranged on each side of the worm gear 9. The rear ends of arms 17 and 18 are pivotally connected to the upwardly extending portions of the arms 15 and 16. On the lower edge of each of the arms 17 and 18 there is a cam follower such as 19 and these cam followers respectively engage the cams on opposite sides of the worm wheel 13. The arms 17 and 18 include straight portions 20 and 21 and at the outer ends of these straight portions stop devices in the nature of collars 22 and 23 are fast by set screws and the like, and these collars may be secured at various places along the portions 20 and 21. Inwardly of the collars 22 and 23 are sleeves 24 and 25 which are slidable along these straight portions 20 and 21. Fast on the straight portions 20 and 21 so as to be adjustable therealong and preferably arranged in spaced relation with the collars 22 and 23 are stop devices in the nature of collars 26 and 27 which may be retained in position by set screws. Disposed about the straight portions 20 and 21 intermediate the sleeves 24 and 25 and the collars 26 and 27 are springs 28 and 29 and normally these springs are expanded to urge the sleeves 24 and 25 into engagement with the collars 22 and 23. Depending from the collars 26 and 27 are bifurcated portions in which pulleys 30 and 31 are rotatably mounted. Other pulleys 32 and 33 are rotatably mounted on the bearing 6. At the end of the sleeve 24 disposed toward the collar 26 is an eyelet 34. One end of a cable or string 35 is secured in the eyelet 34 and is passed over the pulley 30 and about the pulley 32 and through an opening 36 in the table 1 and about a pulley 37 rotatably mounted in a bracket 38 fast on the underside of the table and the end of the string 35 is attached to the free end of a chain 39 adapted to be wound about the shaft 40 which is supported in the machine in a well understood manner (not illustrated in the drawing) and which has a hand wheel 41 at the forward end thereof. At the end of the

100
105
110

sleeve 25 disposed toward the collar 27 is an eyelet 42. One end of a cable or string 43 is secured to this eyelet 42 and the string is passed about the pulley 31 and the pulley 33 and through 5 the opening 36 and about the pulley 37 and is secured to the end of the chain 39. Normally the sleeves 24 and 25 are urged into engagement with the collars 22 and 23 by the springs 28 and 29. As the chain 39 is wound on the shaft 40, 10 the strings 35 and 43 are pulled toward said shaft and therefore these strings act to move the sleeves 24 and 25 along the straight portions 20 and 21 toward the stop collars 26 and 27. At 15 the ends of the strings 24 and 25 opposite that to which the eyelets 34 and 42 are fast are eyelets 44 and 45. A string or cable 46 is fastened to the eyelet 44 and extends to an operating member in the pick-up device 4. A string or cable 47 is fast to the eyelet 45 and extends to 20 an operating member in the pick-up device 4. A cross cable or guy 48 is fast to the eyelet 34 and to the string 46 at a point spaced from the eyelet 44. Fast on the shaft 7 is an arm 49 to which a link 50 is pivotally connected and a 25 button 51 is provided at the forward end of the link 50. In use, rotation of the shaft 8 is begun whereupon the worm gear 9 is rotated to rotate the worm wheel 13 whereby the cams 14 are rotated. The operator of the machine grasps the 30 wheel 41 in one hand and the button 51 in the other hand. When the parts are in the at rest position shown in the drawing, the cam followers 19 rest on dwells on the cams 14 and the arms 17 and 18 are held in an upper position 35 with the straight portion 20 of the arm 17 in a plane slightly above the plane in which the straight portion 21 of the arm 18 is disposed. This disposition of these straight portions so arranges the cables 46 and 47 and the relatively 40 pivotal parts of the pick-up device or bucket 4 that the pick-up device is held open as is illustrated. As the cams continue to rotate, depressions thereon move into alignment with the cam followers 19 whereupon the arms 17 and 18 are lowered and therefore the pick-up device 4 is 45 lowered. Prior to and during the time the pick-up device 4 is being lowered, the operator winds and unwinds the chain 39 which causes the sleeves 24 and 25 to move into different positions 50 along the straight portions 20 and 21 whereby the position of the pick-up device 4 transversely of the table 1 is regulated and at this time by moving the button 51 in and out the shaft 7 55 is rotated and therefore the arms 17 and 18 are moved on an arc whereby the pick-up device 4 is moved longitudinally of the table 1. By this combined transverse and longitudinal movement of the pick-up device 4, the operator 60 of the machine arranges said pick-up device at a position over the prize he desires and when the depressions on the cams move into alignment with the cam followers to permit the arms to lower, the pick-up device moves downwardly 65 into position about the prize the operator desires. After the pick-up device moves down around the article desired by the operator, a further depression on the cam 14 engaged by the cam follower 19 on the arm 17 moves into 70 alignment with this cam follower and the straight portion 20 of the arm 17 moves into or close to the plane of the straight portion 21 of the arm 18. This lowers the cable 46 but since the cable 75 47 is now lowered, the portion of the bucket secured to the cable 47 tends to remain stationary while the portion of the bucket connected to the

cable 46 is permitted to pivot relative to the other part, and this has the effect of closing the jaws of the bucket or pick-up device 4. As the cam followers, immediately after the lowering of the straight portion 20, engage rises on 80 the cams both the straight portions rise together which permits the jaws of the pick-up device to remain closed and grasping the article desired by the operator. The operator then manipulates the button 51 to turn the shaft 7 to bring it into alignment with the opening 2 and during 85 this time the cam follower on the arm moves onto the rise on the cam and following this the cam follower on the arm 17 engages a further rise on the cam and in this way additionally 90 elevates the straight portion 20 the jaws of the pick-up device 4 are separated since again the jaw connected to the cable 47 tends to remain stationary whereas the jaw connected to the cable 46 is moved away from said jaw connected to the cable 47 and therefore the pick-up device 95 opens whereupon the article retained thereby falls through the opening 2 into the discharge chute and passes out of the machine.

The arms 17 and 18 are formed in one piece 100 and inasmuch as the parts carried thereby are exposed to view, proper movement of the sleeves 24 and 25 along the straight portions 20 and 21 of the arms is assured. Furthermore, the breakage of one of the springs or improper movement of the sleeves along the arms may be readily determined. Moreover, by providing the adjustable stop collars 22 and 23 and 26 and 27, the movement of the sleeves along the straight portions of the arms may be confined within 110 definite predetermined limits and in this way adjustability of the operation of the machine is provided.

While I have illustrated and described a selected embodiment of my invention it is to be 115 understood that this is capable of variation and modification and I therefore do not wish to be limited to the precise details set forth but desire to avail myself of such changes and alterations as fall within the purview of the following claims.

I claim:

1. In an amusement machine, a pick-up device, a pair of arms, sleeves mounted on said arms for movement therealong, means supporting said pick-up device from said sleeves, means for moving said sleeves along said arms, and stop devices mounted on each of said arms on opposite sides of said sleeves for limiting movement of said sleeves along said arms. 125
2. In an amusement machine, a pick-up device, a pair of arms, sleeves mounted on said arms for movement therealong, flexible means supporting said pick-up device from said sleeves, yieldable means on said arms and urging said sleeves in one direction, means for moving said sleeves along said arms against the action of said yieldable means, and stop devices mounted on each of said arms on opposite sides of said sleeves for limiting movement of said sleeves along said arms. 130
3. In an amusement machine, a pick-up device, a pair of arms, sleeves mounted on said arms for movement therealong, means supporting said pick-up device from said sleeves, adjustable stop devices mounted on each of said arms on opposite sides of said sleeves for limiting movement of said sleeves along said arms, a spring disposed about each of said arms between one end of each sleeve and one of the stop devices 145 and urging the sleeves in one direction, and means 150

for moving said sleeves along said arms against the action of said springs.

4. In an amusement machine, a pick-up device, a pair of arms, sleeves mounted on said arms and movable therealong, means supporting said pick-up device from said sleeves, adjustable stop devices mounted on each of said arms on opposite sides of said sleeves for limiting movement of said sleeves along said arms, a spring disposed about each of said arms between one end of each sleeve and one of the stop devices and urging the sleeves in one direction, guide means on said one of said stop devices, and means connected to said sleeves and directed about said guide means for moving said sleeves along said arms against the action of said springs.

5. In an amusement machine, a pick-up device, a pair of arms, means for supporting said arms for movement about a center, means for raising and lowering said arms, sleeves mounted on said arms for movement therealong, means supporting said pick-up device from said sleeves, stop devices on each of said arms on opposite sides of said sleeves for limiting movement of said sleeves along said arms, means for moving said sleeves along said arms, and means for moving said arms about said center.
